J. V. WASHBURNE,
WINDOW SHADE ROLLER,
APPLICATION FILED FEB. 11, 1910.

1,149,879.

Patented Aug. 10, 1915.

Fig. 1

UNITED STATES PATENT OFFICE.

JAMES V. WASHBURN, OF FULTON, NEW YORK.

WINDOW-SHADE ROLLER.

1,149,879.

Specification of Letters Patent. Patented Aug. 10, 1915.

Application filed February 11, 1910. Serial No. 543,229.

To all whom it may concern:

Be it known that I, JAMES V. WASHBURN, a citizen of the United States, and resident of Fulton, in the county of Oswego, in the State of New York, have invented new and useful Improvements in Window-Shade Rollers, of which the following, taken in connection with the accompanying drawings, is a full, clear, and exact description.

10 This invention pertains to shade-rollers of the class in which the roller proper is formed hollow for a portion of its length for the reception of a stationary supporting-spindle which is surrounded by a spiral-spring connected at its respective ends to the roller and spindle and serving to automatically wind the shade upon the roller, which latter has fastened to one of its ends a plate or disk carrying a pair of catches co-20 operating with a notched spear secured in the adjacent end of the spindle to hold the roller against the unwinding action of the spring.

25 The present invention is particularly related to the type of shade-rollers in which the spiral-spring has its inner end attached to the spindle and its outer end connected to the roller.

30 The object of this invention is to provide a simple rigid and reliable attachment of the spiral-spring to the catch-carrying disk or plate secured to the roller, and at the same time produce a structure which will permit the parts to be easily and quickly 35 assembled.

To that end the invention consists essentially in the combination of a hollow roller, a stationary spindle disposed in one end of said roller, and provided in its outer end 40 with a so-called spear engaging a supporting-bracket, and a spiral-spring surrounding the spindle and having its inner end secured to the corresponding end of said spindle, and a flat metal disk rigidly secured on 45 the end of the roller and provided with a central annular opening through which the aforesaid spear passes, said disk being formed on its inner face with a circular channel which partly surrounds the aperture and is opened at both ends, and the said 50 spring having its outer end portion secured in said channel.

Furthermore, the invention resides in the novel manner of forming the circular channel on the disk.

55 In the accompanying drawings Figure 1

is partly a side view and partly a longitudinal section of a portion of a shade-roller showing the spiral-spring attached directly to the catch-carrying disk in accordance 60 with my invention; Fig. 2 is an enlarged transverse section on the dotted line —W—W— in Fig. 1; Fig. 3 is an enlarged transverse section of the catch-carrying disk detached and a portion of the spring attached 65 thereto; Fig. 4 is an enlarged end view of the roller with cap removed; Fig. 5 is an enlarged detail inner face view of said disk.

Like characters of reference indicate like parts in the several views of the drawings.

—1— denotes the roller which is usually composed of wood and is provided with a longitudinal bore —2— extending from one end partway the length thereof, to which roller is attached the shade —3— designed 70 to be wound thereupon in the well known manner.

—4— denotes the usual cylindrical wooden spindle which is disposed within the bore —2— and is of such diameter as to allow 80 it to be surrounded by the spiral-spring —5— which is common to all shade-rollers of this character.

The spindle passes freely through the spiral-spring and may have the inner end of 85 the spring secured to its corresponding end in any suitable and convenient manner. However, I prefer to reduce the diameter of the end helices of the spring so as to cause several of the helices to closely embrace the 90 spindle, and bend the end portion of the spring so as to be seated in the end of a short diametric slot —5x— extending from the end of the spindle.

In the outer end is rigidly secured the 95 usual metal spear —6— which is formed with an annular hub —7— provided with two diametrically disposed notches —8—, the outer end portion of which spear is flattened, as indicated at —9—, and seated in 100 the usual correspondingly shaped elongated opening —10— provided in the well known supporting-bracket —11— designed to be fastened to the window-casing.

By the rigid attachment of the spear to 105 the spindle and the locking engagement of the spear with the bracket, the said spindle is held against rotation.

To the end of the roller —1— adjacent to the spear is fixed a catch-carrying member 110 —12— which may be of any suitable or well known form and is detachably secured to

the said roller by any suitable means. I prefer however to use the form of a disk shown and described in the Letters Patent 912,636 granted to me on the 16th day of 5 February 1909, and consisting of a flat square disk composed of sheet metal and having its corner portions bent at right angles to form tongues —13—13— which pierce the end of the roller at its peripheral 10 portion whereby the disk is prevented from slipping circumferentially on the roller. The said disk is formed with a central circular aperture —14— through which aforesaid spear —6— extends, the portion of the 15 metal at the edge of the aperture being flared toward the end of the spindle to form a loose journal for the roller upon the inner end portion of the hub —7—, and whereby the disk abuts against the adjacent end of 20 the spindle.

—15—15— denote a pair of catches which are carried on the outer face of the disk —12— and may be of any well-known form.

In the present instance the said catches 25 are of the form shown and described in my Letters Patent referred to and they consist of flat plates adapted to slide on the outer face of the disk and having their adjacent edges cut out to accommodate the hub —7— 30 on the spear —6— when the said plates move toward the said hub. The said edges of the plates are formed with tongues —16—16— adapted to engage the aforesaid notches —8—8—, one at a time. Said catch- 35 plates are supported on the disk by providing the latter with flanges —17—17—18—18— formed by bending the marginal portions of the disk at right angles. The two opposite flanges —17—17— terminate in inwardly 40 projecting lips —19—19— to serve as guards for the sliding plates.

Inasmuch as this invention does not pertain to the catch-plates or their carrying-disk, further description and illustration of 45 said parts are unnecessary.

As hereinafter stated, the present invention resides in the attachment of the outer end of the spiral-spring —5—.

When catches of the aforesaid form are 50 employed, I prefer to connect the spring

directly to the disk —12—. To effect this connection, the disk is provided on its inner face with a circular-channel —20— which is open at both ends to permit the end helix of the spring to be threaded therethrough. 55 The end portion of the wire is extended sufficiently to allow it to be clenched onto the adjacent end of the channel.

To produce this channel, the sheet metal disk is subjected to the action of a die-press 60 which is designed to slit the disk on two short radial lines of the same length and which are disposed equidistantly from the central aperture of the disk, and coincidently with this slitting operation, the metal is thrown out on one face of the disk in the form of a segmental rib of U shape cross-section and extending from one slit to the other and disposed concentric with the central aperture. 70

I prefer to extend the said channel half-way around the central aperture so as to insure a strong hold of the spring on the disk.

What I claim is:—

1. In a shade roller, a one-piece catch-carrying plate having a central circular opening and a semi-circular channeled rib concentric with said opening and wholly at the inner side of the plane of the plate, the channel extending lengthwise of the rib and opening at both ends thereof to receive the end of a roller-retracting spring. 80

2. In a shade roller, a one-piece catch-carrying plate having its opposite edges provided with outwardly projecting catch-guiding flanges in combination with opposed radially sliding catches guided by said flanges, said plate having a circular central opening and an inwardly projecting concentric rib provided with a lengthwise channel extending across and to opposite sides of the meeting edges of said catches and open at both ends to receive the end of a roller-retracting spring. 90

JAMES V. WASHBURNE.
